UNITED STATES PATENT OFFICE

90,935

DESIGN FOR A CYCLOMETER CLOCK CASE

Robert D. Barrett, New York, N. Y.

Application July 8, 1933. Serial No. 48,670

Term of patent 7 years

To all whom it may concern:

Be it known that I, ROBERT D. BARRETT, a citizen of the United States, and a resident of New York, borough of Manhattan, in the county of New York and State of New York, have invented the new, original, and ornamental Design for a Cyclometer Clock Case, of which the following is a specification.

Reference is had to the accompanying draw-

ing, forming part thereof, wherein—

Figure 1 is a perspective view of a cyclometer clock case, showing my new design.

Figure 2 is a plan view.

I claim:—

The ornamental design for a cyclometer clock case, substantially as shown.

ROBERT D. BARRETT.
